H. K. SANDELL

RADIO FREQUENCY TRANSFORMER

Filed March 5, 1923

Inventor:

*Henry K. Sandell,
Bydstrupstræde, Christiania, Niss.
Attest.*

UNITED STATES PATENT OFFICE.

HENRY K. SANDELL, OF CHICAGO, ILLINOIS.

RADIOFREQUENCY TRANSFORMER.

Application filed March 5, 1923. Serial No. 622,871.

To all whom it may concern:

Be it known that I, HENRY K. SANDELL, a citizen of the United States, residing at Chicago, in the county of Cook and State 5 of Illinois, have invented a new and useful Improvement in Radiofrequency Transformers, of which the following is a specification.

This invention relates to radio frequency 10 transformer and the like, and is particularly adapted to be used for radio frequency amplification in radio receiving sets.

The invention is fully described in the following specification and shown in the accompanying drawings in which:

Figure 1 is an enlarged side elevation of an embodiment of the invention.

Fig. 2 is a partial vertical section through the transformer on the line 2 of Fig. 3;

Fig. 3 is a horizontal section on the line 3 of Fig. 2 and

Fig. 4 is a side elevation of the primary coil showing the soft iron wires of the core as before being bent around the secondary.

The embodiment illustrated comprises a primary coil 10 wound about a tube 11 of insulating material in which is placed a series of wires 12 consisting of very soft iron.

Over the primary coil 10 is placed a spool 13 of insulating material having a series of annular compartments or grooves 14 therein in each of which is wound a number of turns of wire forming a secondary coil 15. This winding is accomplished by starting at one end of the spool, winding the desired number of turns in the first groove carrying the wire through a slot (not shown) to the next groove, winding that, and proceeding through each succeeding groove to the opposite end.

With the secondary winding placed over the primary winding the wires 12 are then bent around the secondary so that their ends overlap. These ends are then secured in any desired manner, and these windings are enclosed within a housing 16, the two ends of the primary winding being carried to binding posts 17 and 18, and the two ends of the secondary to binding posts 19 and 20 in the base 21 whereby the transformer may be readily inserted into a radio receiving set.

A supporting bracket 22 preferably of insulating material is secured to the housing 16 and has an adjusting screw 23 threaded

therein. This screw is operable by a knob 24 of insulating material and carries at its lower end an insulating member 25 to which is attached a number of soft iron wires 26 which are suspended in the hollow tube 11.

In practice, I find that for the present broadcasting range, I obtain the best results by using 200 turns of No. 34 cotton covered wire, in the primary winding 10, 65 365 turns of the same wire in the secondary winding 15 and 24 soft iron wires in the core 12 with about seven or eight pieces in the movable core 26. Thus the primary is aperiodic and the secondary is periodic or 70 resonant for the present broadcasting range.

With this arrangement the transformer is very delicate, the response obtainable being varied by raising and lowering the wires 26 of the movable core. 75

By raising and lowering the movable core the desaturation time of the iron is varied, and by properly choosing the values, this time may be brought into step or resonance with the natural period of inductance of 80 the secondary coil. In other words, varying the iron in the core varies the frequency of the secondary coil so that by this means, the resonance of the circuit in which the secondary coil is placed may be tuned. 85 When this occurs, the strength of current flowing in this coil is greatly increased. The relation between the soft iron core and the secondary is very sensitive to small changes in either, while relatively large 90 changes in the primary are permissible without materially altering the operation of the transformer.

If desired short pieces of the soft iron wire may be embedded in a non-magnetic 95 substance to form the movable core and by properly proportioning this, the wires 12 may be omitted altogether.

While I have shown and described certain embodiments of my invention, it is to be 100 understood that it is capable of many modifications. Changes, therefore, in the construction and arrangement may be made without departing from the spirit and scope of the invention as disclosed in the appended 105 claims, in which it is my intention to claim all novelty inherent in my invention as broadly as possible in view of the prior art.

What I regard as new and desire to secure by Letters Patent, is:

1. A radio-frequency transformer comprising an aperiodic primary winding, a sec-

ondary winding periodic to the frequencies of the band of waves it is desired to receive, said windings being substantially coaxial, a fixed soft iron core and a soft iron core movable into and out of inductive relation to said windings, whereby the frequency of the circuit in which the secondary winding is placed may be tuned.

2. A radio-frequency transformer comprising an aperiodic primary winding, a periodic secondary winding, said windings being substantially coaxial, a fixed soft iron core consisting of a plurality of small soft iron wires, and a soft iron core movable into and out of inductive relation to said windings, whereby the frequency of the circuit in which the secondary winding is placed may be tuned.

3. A radio-frequency transformer comprising an aperiodic primary winding, a periodic secondary winding, said windings being substantially coaxial, a fixed soft iron core consisting of a plurality of small soft

iron wires, the ends of each wire passing around said windings and being brought into substantially overlapping position, and a soft iron core movable into and out of inductive relation to said windings, whereby the frequency of the circuit in which the secondary winding is placed may be tuned.

4. A radio-frequency transformer comprising an aperiodic primary winding, a periodic secondary winding, said windings being substantially coaxial, a fixed soft iron core, and a core of soft iron wires movable into and out of inductive relation to said windings, whereby the frequency of the circuit in which the secondary winding is placed may be tuned.

5. In combination, a winding having a natural frequency within the radio range, a fixed soft iron core, and a magnetic core movable therein for varying the frequency of said winding.

HENRY K. SANDELL.
